UNITED STATES PATENT OFFICE

2,496,810

EDUCATIONAL LINK

Ralph A. Nerrie, Fayson Lake, Butler, N. J.

Application December 11, 1946, Serial No. 715,457

2 Claims. (Cl. 35—71)

1

This invention relates to educational devices or toys and, in particular, to the provision of such a new and improved device or toy by means of which each of the letters of the alphabet as well as numerals, symbols, etc., may be quite closely simulated or represented by children of letter-learning ages, thereby combining education with entertainment and amusement.

It is the primary object of this invention to provide such a new and improved device which is capable of simulating letters, numerals, and symbols with curved legs or branches, and with both curved and straight legs or branches, substantially as closely as letters, numerals, and symbols with straight legs or branches only.

It is a further object of this invention to provide such a device which is of simple, sturdy construction and capable of cheap production in widely varying materials.

It is a further object of this invention to provide such a device or toy which incorporates plural complementary, relatively movable sections or members which are capable of being selectively arranged, by units, to simulate either straight-edged or curved-edged legs or branches as parts of various letters, numerals or symbols, and the like.

These and other objects and advantages of the invention will hereinafter appear from the following description and the accompanying drawing forming a part thereof, and will be pointed out in the appended claims.

In the drawing:

Fig. 1 is a plan view of one preferred form of my device extended to illustrate the members thereof and the manner in which they are connected;

Fig. 2 is a plan view of the device of Fig. 1 with the parts collapsed;

Fig. 3 is a view, in side elevation of the structure shown in Fig. 2;

Fig. 4 is a fragmentary section taken through one joint, along the plane indicated by the line 4—4 in Fig. 2, and showing the details of the connection provided between two adjacent main members and an intervening auxiliary member, the spacing therebetween being exaggerated in the interest of clear disclosure;

Fig. 5 is a plan view of the device with the parts in position for forming the letter "B," a letter having both straight and curved legs, portions, or branches;

Fig. 6 is a plan view of the device with the parts in position for forming the letter "L," a

2

letter having only straight or straight-edged legs or branches; and

Fig. 7 is a plan view of the device with the parts in position for forming the letter "C," a letter having only curved or curved-edged legs or branches.

The illustrative embodiment of my invention shown in Figs. 1-7 comprises a plurality of elongated, similar main members or sections 10, 11, 12, 13, 14, 15 and 16 pivotally connected in substantial end-to-end relation, as hereinafter described in detail, to form an articulated elongated structure of which each of these members or sections 10-16 is a constituent section or part.

At each joint between the ends of adjacent members 10-16 one of a plurality of similar auxiliary members of sections 17, 18, 19, 20, 21 and 22 is pivotally secured between the end portions of the adjacent main portions or sections 10-16. Another, similar, auxiliary member or section 23 is pivotally secured to the outer end portion of the main member or section 16 at one end of the main structure. The main member or section 10 at the opposite end of the main structure is, preferably, for the sake of appearance, un-apertured at its outer end, being otherwise similar in every respect to each of the other members or sections 11-16.

As shown in Fig. 4, the pivotal connection between the respective main and auxiliary members at each joint may be accomplished by means of similar aligned apertures 24 in each end portion. A hollow rivet, eyelet, or grommet 25 extends through each set of apertures 24 and clampingly secures the pivotally connected end portions closely together to create the desired degree of frictional resistance to relative pivotal movement therebetween. Of course, such other known connecting means may be substituted as is most appropriate to the particular material from which the main and auxiliary members or sections are formed.

Each of the main members or sections 10-16 has a straight side edge and a curved side edge; the auxiliary members or sections 17-23 each also have one straight side edge and one curved or arcuate side edge, the curved or arcuate side edges of the main and auxiliary members or sections being converse, i. e. concave in one case and convex in the other. Preferably, they are substantially concentric as shown in Figs. 5 and 7.

In the illustrative embodiment shown, the side edges of the main members or sections 10-16 are designated 26 and 27, the edges 26 being straight and the edges 27 being curved and con-

cave. The side edges of the auxiliary members or sections 17-23 are designated 28 and 29, the edges 28 being straight and the opposite edges 29 being curved and convex. If desired, the curved edges of the main members or sections may be made convex and the curved edges of the auxiliary members or sections made concave.

Since the auxiliary members 17-23 are pivotally connected between adjacent main members 10-16, the entire structure may be collapsed or folded in "jack-knife" relation as shown in Figs. 2 and 3. In such position the straight sides 26 and 28 of the main and auxiliary members or sections (see 10 and 17, Fig. 2) form the side portions of the outline to define a straight leg or branch of a letter such as the capital "L" shown in Fig. 6.

By swinging the auxiliary member 17 counter-clockwise as seen in Fig. 2, the arcuate edges 27 and 29 may be made to define the side edges of a curved or arcuate branch or leg of a letter such as the capital "C" shown in Fig. 7.

An important feature of the invention which greatly simplifies and cheapens the manufacture thereof is the fact that each of the auxiliary members or sections 17-23 is identical, and, with the exception of the optional omission of the aperture 24 at one end of one main member or section (10, Fig. 1), the same is also true of the main members or sections 10-16; the rivets, eyelets or grommets 25 are likewise identical. Thus the device is made up of a plurality of each of three parts, namely main members or sections and auxiliary members or sections, both of which may readily and cheaply die cut from any sheet material such as non-metallic plastic sheeting, metal, wood, paper or composition, and the attaching elements 25 which are cheap and readily procurable and attachable commercial products.

A further important feature of the invention resides in the fact that each set or pair of complementary members, such as main member 13 and auxiliary member 20, may selectively be positioned with their straight edges 26 and 28 outwardly to form a straight or straight-edged leg or branch as shown in Fig. 6, or with their curved or arcuate edges 27 and 29 outwardly to form a curved or curved-edged leg or branch as shown in Fig. 7. While the curved edges 27 of the main members 10-16 may be omitted, it is preferred that these edges be curved for closest possible simulation of the smooth continuous delineating or defining outer edges of letters, numerals or symbols, etc., which are comprised either partly or entirely of curved legs, branches or portions. See, for instance, the capital B, Fig. 5 and the

capital C, Fig. 7. As stated before, the surfaces 27 and 29 are preferably concentric, as shown.

From the above description it will clearly appear that I have provided a new and improved educational device or toy possessed of the above described properties and characteristics and which is possessed also of a high degree of versatility and scope in simulating alphabetical letters both capital and lower case, numerals, symbols, etc., and which, because of the closeness with which letters, numerals, etc., may be simulated, is highly attractive to children by reason of its appeal to their imitative capacities.

It is, of course, to be understood that the above description is merely illustrative and in nowise limiting and that I desire to comprehend within my invention such modifications as are included within the scope of the following claims.

Having thus fully described my invention, what I claim as new and desire to secure by Letters Patent is:

1. In an educational device of the class described, a jointed elongated body comprising a plurality of main strip members pivotally connected in series, and a plurality of auxiliary strip members each free at one end and having common pivotal connection with adjacent main strip members at their other ends, said main strip members and said auxiliary strip members each having one curved side edge and one straight side edge, each of said auxiliary strip members being selectively adjustable angularly with respect to an adjacent main strip member to form therewith a section with its side edges defined either by said straight edges or said curved edges.

2. The structure defined in claim 1, wherein the curved side edges of said auxiliary strip members are concentric with respect to the curved side edges of cooperating adjacent main strip members in predetermined positions of relative adjustment with respect thereto.

RALPH A. NERRIE.
